(57) **CLAIM**

The ornamental design for a searing topper, as shown and described.

DESCRIPTION

FIG. 1 is a top plan view of a searing topper showing my new design;

FIG. 2 is a bottom view thereof;

FIG. 3 is an enlarged scale partial view of the portion depicted within the oval bearing the numeral 3 in FIG. 2;

FIG. 4 is an enlarged scale partial view of the portion depicted within the oval bearing the numeral 4 in FIG. 2;

FIG. 5 is a front elevational view thereof;

FIG. 6 is a rear elevational view thereof;

FIG. 7 is a right side elevational view thereof; the opposite side being a mirror image thereof;

FIG. 8 is an enlarged scale fragmentary right side elevational view thereof;

FIG. 9 is a top plan view thereof with panels folded over one another;

FIG. 10 is a bottom view thereof with the panels in their FIG. 9 position;

FIG. 11 is a front elevational view thereof with the panels in their FIG. 9 position;

FIG. 12 is a rear elevational view thereof with the panels in their FIG. 9 position; and,

FIG. 13 is a left side elevational view thereof; with the panels in their FIG. 9 position, the opposite side being a mirror image thereof. The broken line showings of the apertures form no part of the claimed design.
